UNITED STATES PATENT OFFICE.

ROBERT P. BOLLING, OF DETROIT, MICHIGAN.

BAKE OVEN.

Application filed December 18, 1922. Serial No. 607,544.

This invention relates to a bake oven and especially to a rotating shelf bake oven which is calculated to secure a uniform application of heat to all the stuff undergoing the baking operation. In my prior Patent No. 1,433,598, October 31, 1922, I have described and claimed a bake oven having rotating shelves, however, this bake oven is provided with a central spindle or shaft which limits the size of the pans that may be inserted and somewhat interferes with the free arrangement and sliding of the pans on the shelves.

It is the object of the present invention to provide an arrangement in which a vertical series of shelves is supported and driven in rotary movement and a center shaft entirely eliminated making the full surface of the shelf available for the pans.

A further object of the invention is an arrangement for evenly distributing and using the heat emitted from the products of combustion over the stuff being baked so as to nicely brown the top without burning the same. This provides above the pans a zone of concentrated heat, the batch being exposed to the concentrated heat during only a portion of one revolution. It will not be burned but the intense heat will brown it and give it a better color than is possible with just the general heat emitted from the burner or fire box. This will more fully appear when the construction is understood.

In the drawings:—

Fig. 1 is an elevation partly in section of the oven.

Fig. 2 is a vertical cross-section of the same taken from front to back.

Fig. 3 is a plan view of the oven.

Fig. 4 is a detail showing the shelf construction and the girder construction.

Fig. 5 is a section on the line 5—5 of Fig. 4.

The oven comprises a lower channel ring *a* and an upper channel ring *b* connected by the long vertical bolts *c* which bolt the rings over the upper and lower ends of the outer cylindrical wall *d* and the inner cylindrical wall *e*. The space between the walls is packed with suitable insulating material. The sheet metal top *g* and bottom *f* is provided, as are also suitable legs *h*. The fire pot is designated *i* and in this may be burned either coal, wood or hydrocarbon vapor.

There is supported one on each side of the

oven an upright post *j*. These posts are adapted to support the cross girders *k* which are roughly of inverted channel shape but which are preferably special castings made for the job. One end as shown in Fig. 4 of 60 this casting is forked to engage not only the adjoining post *k* but to form a support or arm *m* for the rotating shaft *o*. This rotating shaft carries a driving pinion *p* which engages with the external teeth of the ring *r* secured to the outside of the shelf, consequently, when the shaft *o* is rotated by means of the worm *n* the worm gear *q*, and the motor *M* the entire series of shelves is 65 driven in rotation.

The cross girders are provided with central bosses *s* that form bearings for the studs *t* and supporting flanges *y* which support the shelves rotatably on the girders. These studs are so short that they do not reach 70 down in the pan space between two adjoining shelves so as to interfere in any way with the arrangement of the pans.

A plurality of laterally extending arms 1 are secured to the central supporting flange 80 portion *y*. The shelves 2 are secured to these arms by means of countersunk stove bolts 3. The ring *r* is similarly secured to the under-side of the shelf by the countersunk bolts 4 leaving the upper surface of the 85 shelves free from all obstructions.

The flue arrangement I believe to be absolutely novel in connection with ovens having rotating shelves. Products of combustion are led from the fire pot to the flue *u*, and are then led to the side wall of the oven and up through the flue *v*. The flue then turns and runs across the back of the oven under the second shelf and it is here designated *w*. This creates a pronounced 90 hot zone directly above the pans on the lower shelf and subjects them to a high but temporary heat as they rotate, thereby nicely browning the stuff contained in the pans. The flue *w* crosses and is led up through the 95 opposite side wall of the oven and again crosses the back of the oven above the second shelf and in a like manner crosses the back of the oven above the third shelf forming what might be called roughly, a zig-zagging of the flue carrying the products of combustion across the shelves and above each individual shelf at one portion of the oven.

I am well aware of the fact that rotary

shelves have been driven in ovens heretofore from the outside of the shelf, but so far as I know, no one has heretofore provided a permanent support in the oven for a vertical series of rotating shelves supported and driven so that the pan space between the shelves is in no way obstructed for the sliding and convenient arrangement of the bake pans. This I consider a valuable improvement.

What I claim is:—

1. In an oven of the character described, the combination of an oven shell provided with an open interior, a vertical series of 15 rotating shelves having a diameter approximating the diameter of the oven interior, said shelves arranged to allow heated air to rise past the shelves and permanently supported therein, means for supporting said shelves leaving free and unobstructed the pan space between said shelves and also leaving the heated air free to circulate, and means for continuously driving said shelves in rotation, leaving the space between said shelves free and unobstructed.

2. In a bake oven of the character described, the combination of an oven shell, a vertical series of shelves supported therein and having a diameter approximating the 30 diameter of the oven interior, cross girders rotatably supporting the shelves fixedly within the shell without interfering with the pan space between the shelves, and means for driving said shelves in rotation leaving the pan space between the shelves free from 35 obstruction.

3. In a bake oven of the character described, the combination of an oven shell, a vertical series of shelves contained therein and having a diameter approximating that 40 of the oven interior, cross girders permanently supported in the oven at each end for supporting the individual shelves and provided with bearings for supporting the center of each shelf rotatably, and means

for engaging the outside of the shelves for rotating the same.

4. In a bake oven of the character described, the combination of an oven shell, a pair of posts supported in the oven shell, cross girders supported upon the posts and provided with bearings at the center of the oven, a vertical series of shelves supported rotatably at their center upon the bearings of the cross girders and means for engaging 55 the outside periphery of the shelf to rotate the same.

5. In an oven of the character described, the combination of an oven shell, a pair of 60 posts contained therein, cross girders supported by the posts and provided with center bearings and having at one end sidewise extending arms forming rotating shaft bearings, a vertical series of shelves supported rotatably at their centers in the first-named 65 bearings afforded by the girders and a rotating shaft supported in the bearings furnished by the arms of the girders and provided with a driving connection for engaging the periphery of the shelves to drive the 70 same in rotation.

6. In a bake oven of the character described, the combination of a shell, a firebox located in the shell near the bottom, one or more rotatably supported shelves located 75 above the fire box and arranged so that the space above the shelf or shelves has free communication with the space about the fire box, means for continuously rotating the shelf or shelves, and a flue connected with the 80 interior of the fire box for leading the products of combustion from the fire box up over the rotating shelf or shelves and across a small portion only of the same to furnish a limited zone of intense heat to brown the 85 baking goods as the shelf rotates the batch through this zone.

In testimony whereof I affix my signature.

ROBERT P. BOLLING.
